UNITED STATES PATENT OFFICE.

LEON BUSH, OF MINNEAPOLIS, MINNESOTA, ASSIGNOR TO WILLIAM EDWIN NELSON,
OF MINNEAPOLIS, MINNESOTA.

STRIP SHINGLE.

Application filed February 11, 1924. Serial No. 692,156.

This invention relates to improvements in strip shingles, for covering the roofs or walls of buildings, formed preferably of roofing felt, or material of similar nature, with a mineral covering or surface usually formed of finely divided slate, stone, gravel, or similar material.

The present invention is an improvement on the strip shingle shown and described in Letters Patent of the United States issued to me August 14th, 1923, No. 1,464,492.

The invention consists generally in the constructions and combinations hereinafter described and particularly pointed out in the claims.

In the accompanying drawings,

Figure 1 is a plan view of a single shingle embodying my invention.

Figure 2 is a plan of a sheet of material, or a portion of a sheet, illustrating the manner in which the strip shingles may be cut therefrom.

Figure 3 is a plan view showing a preferred manner of laying the shingles to form a roof or wall covering.

In the drawing, 1 represents the body portion of the strip shingle, which may be formed, in the usual way, of a foundation sheet of wool felt, with a coating or layer 30 of pitch, asphalt, or the like on one surface of the felt, and a layer of crushed slate, stone, gravel, or similar material pressed into the coating and held in place thereby.

I form, at one edge of the body, projecting extensions, or butts, 2, 2, here shown of rectangular form, separating spaces 3, 3, being provided, each equal in outline or contour, and area to the outline, contour and area of each of the butts 2, so that a rectangular sheet, such as shown in Figure 2, may be divided as indicated by the dotted lines, 5, 5, and 7, 7, extending longitudinally of the sheet, and the transverse lines 6, 6, and 8, 8.

In starting manufacture of the shingle from a double strip as indicated in Figure 2, there will be at the end of the strip two small corners, e, e, which will be wasted, but there will be no further waste until the opposite end of the sheet is reached. In producing this strip shingle the butts, 2, 2, are located at the same distance from the ends of the body of the shingle, that is to say, the line a—f, that measures the distance from the right hand butt to the end of the shingle strip is equal to the line a—g that measures

the distance from the left hand butt to the left hand end of the shingle, and each of these lines is equal to one-half the length of the line e—c which measures the distance between the inner edges of the butts and the 60 vertical lengths of the butts 2—2 will be one-half the horizontal width of the separating spaces 3—3 which in turn are substantially equal the vertical width to the body 1 of the shingle which enables me to cut the 65 shingles from rolls as above indicated without waste except at the corners of the ends of the roll. This produces an entirely symmetrical shingle, and when the shingles are laid on a roof in overlapping relation, as illustrated in Figure 3 of the drawings, the roof will not only have a symmetrical appearance but every part thereof will have at least two layers of material covering it. 70 Moreover as will be observed from an inspection of Fig. 3, the shingles are arranged on the roof in the ordinary courses with the ends of the body portions of the shingles abutting each other. The butts lie flat on the body portion of the shingles of the un- 80 derneath lower course of shingles, the butts having the same contour of the spaces between the butts makes it possible to cut from a single strip of material two sets of shingles on a severing broken line 5—5, Fig. 85 2, without material waste of material. When the shingles of an upper layer are disposed as shown in Fig. 3, from those in the lower layer, the distance of a butt, the joints between the meeting edges of the shingles are 90 broken and the butts extend in vertical relation one directly above the other, and there would always be a double thickness of solid material to break the joints between the butt ends of the body portions of the shingles. I 95 do not limit myself to any particular size or dimensions of the parts, nor to any particular material for forming the same.

I claim as my invention,

1. A strip shingle comprising a body portion having a plurality of separated butts projecting from one edge thereof with sides perpendicular thereto throughout to their ends, the size and contour of each butt corresponding to the size and contour of the separating spaces between two butts, the distance between the outer edge of each butt and the end of the shingle being equal to one-half the distance between the inner edges of the butts and substantially equal to the 110

length of the butt, and the length of the butts being approximately one-half the width of the body of the shingle.

2. A roof comprising courses of shingles, each shingle comprising a body portion having a butt projecting from one edge thereof, each butt being separated a distance from either end of the shingle, each butt on the roof being spread out flat and extending 10 down over the body portion of the shingle or shingles of a lower course of shingles, the size and contour of each butt corresponding to the size and contour of the separating space between two companion butts when 15 the shingles are laid in the ordinary courses on the roof, the ends of the body portions abutting each other, the end edges of the body of the shingle being perpendicular to

the longitudinal edges, the distance between the points where the edges of the butts meet 20 the lower edge of the body of the shingle to the lower edge of the butt in all the shingles of a course being equal to one-half the length of the lower edge of each butt and substantially equal to only half the distance 25 from the top to the bottom of the body of the shingle whereby two sets of shingles may be cut on a single continuous broken line from a rectangular strip of sheet material, the body portion of the shingles being severed from each other on lines extending approximately from the middle point of a separating space between companion butts.

In witness whereof I have hereunto set my hand this 5th day of February, 1924.

LEON BUSH.
